UNITED STATES PATENT OFFICE.

WILLIAM M. GROSS, OF LAS VEGAS, NEVADA.

EXCAVATING AND LOADING MACHINE.

1,332,662.

Specification of Letters Patent.

Patented Mar. 2, 1920.

Application filed December 6, 1916, Serial No. 135,441. Renewed December 4, 1919. Serial No. 342,498.

To all whom it may concern:

Be it known that I, WILLIAM M. GROSS, a citizen of the United States, residing at Las Vegas, in the county of Clark and State 5 of Nevada, have invented new and useful Improvements in Excavating and Loading Machines, of which the following is a specification.

This invention relates to an excavating 10 and loading machine and particularly to a machine for excavating and loading dirt.

It is an object of this invention to provide a machine which may be operated manually or by power to loosen and excavate dirt from embankments or pits and elevate it to a suitable loading level, from which it may be discharged, said machine being light in construction and simple in operation, thereby requiring the attendance of few workmen.

Another object of this invention is to provide a machine of the above character which is so designed as to be flexibly manipulated to excavate and load dirt throughout a wide 25 range of operation without a change in position.

Another object of this invention is to provide excavating means which will loosen and feed the soil to a suitable loading platform, said excavating means being so constructed as to operate continuously irrespective of the quantity of soil fed thereto and the rate of speed at which the loading mechanism operates.

Another object is to provide an excavating 35 machine which will feed its way into an embankment at any level or angle at which it is started.

Another object is to provide an excavating 40 machine which will cut to any desired depth through an embankment after it is once started at the desired level, and regardless of the amount of the embankment above the level, within reasonable limits.

Another object is to provide adjustable 45 means whereby the depth at which the machine operates may be readily determined and varied as occasion may require.

Another object of this invention is to provide 50 a machine of the above character having a substantial frame work so constructed as to be readily moved from place to place as the work proceeds.

It is a further object to provide an ex-

cavating and loading machine which possesses few movable parts which are liable to become worn or broken.

Other objects will appear hereinafter.

The invention is illustrated, by way of example, in the accompanying drawings in which;

Figure 1 is a view in side elevation illustrating the complete excavating and loading machine as set up for operation.

Fig. 2 is a view in plan showing the excavator and loading platform in their positions between the upright supports provided therefor and illustrating the supporting structure with parts broken away for sake of convenience.

Fig. 3 is a view in elevation illustrating in detail the adjustment means provided for the loaded platform conveyer belt.

Fig. 4 is a view in section and elevation illustrating the mounting provided one of the driving sprockets by which the conveyer belt is driven.

Fig. 5 is a view of the traveling support by which the rear end of the loading platform is held, as seen on the line 5-5 of Fig. 1.

Fig. 6 is a view in section and elevation, as seen on the line 6-6 of Fig. 1 and illustrates the manner in which the forward end of the loading platform is supported.

Fig. 7 is a view in side elevation illustrating a modified form of excavating member adapted to be used in fine soil or sand.

Referring more particularly to the drawings, 10 and 11 are a pair of skid timbers 90 which lie parallel to each other and they rest upon the ground to form a substantial support for the excavating mechanism and serve as runners. Mounted upon the skid are a series of upright supports 12, 13, 14, 95 and 15 which are here shown as being formed of tubular section for the sake of strength and lightness. These members are secured to the skids by means of fittings 16 which are suitably held by bolts 17. The uprights extend perpendicular to their mounting and are parallel to each other. The upper end of each upright is fitted with a fitting 18 adapted to receive the ends of horizontally extending reinforcing pipes which connect the upper ends of the uprights and hold them in rigid relation to each other. Mounted upon reinforcing pipes 19 and 20 which

extend transversely on the machine are a pair of channel track members 21 and 22, upon which a traveling carriage 23 is adapted to travel for a purpose which will be 5 hereinafter set forth.

Secured to and supported by the channel members 21 and 22 at a point midway their length, is a mast 24 which is pivotally mounted upon a casting 25 and extends vertically therefrom to provide a revolving support for a horizontally swinging beam 26. The track beam 26 is formed as set forth in Fig. 5 of the drawings and is supported by truss member 27 which is in turn 10 fastened to a pivot plate 28 within which the upper end of the mast 24 is adapted to rotate. The plate 28 is rigidly held by means of the guy rod 29 which is secured to the channel members 21 and 22 at their 15 rear end. The beam 26 is provided as a track for a traveling carriage 30 adapted to support the forward end of a loading platform or draper 31.

It will thus be seen that the loading platform or draper 31 is movably supported by carriages 23 and 30 which are provided with longitudinal movement along the channel members 21 and 23 and the beam 26. Reference being had to Fig. 5 of the drawings, it 25 will be seen that the carriage 30 is formed with a pair of side plates 31 and 32 adapted to be suspended from shaft 33 of wheel 34 with which the carriage is provided. This wheel is adapted to bear upon the upper 30 face of the beam 26 and is formed with an enlarged central flange adapted to extend between the channels of which the beam is constructed. The side plates 31 and 32 extend downwardly upon opposite sides of the 35 beam and converge there beneath to provide a suitable support for a pivot bolt 36 upon which a pulley 37 is rotatably secured. This pulley is provided to receive a supporting chain 38, one end of which, is fitted with a ring 39 and the other end is provided with a hook 40 adapted to pass through the ring and engage the various links of the chain to 40 raise and lower the forward end of the loading platform. Secured to the ring 39, is a sling 41 which extends downwardly and is held in pivotal engagement with the opposite sides of the frame of the loading platform. This sling is fitted with a lever 42, which may be manipulated to directly raise 45 and lower the forward end of the loading platform.

The rear end of the platform 31 is supported by lengths of chain 42, secured to the frame of the platform upon its opposite 50 sides and engaged by an eye bolt 43 at their upper ends. The eye bolt 43 is secured within the lower end of a hanger rod 44 which depends from the carriage 23 and extends downwardly between the channel 55 track members 21 and 22. This carriage is

provided with a series of wheels 45 formed with enlarged flanges adapted to engage the inner faces of the channels. By means of these two carriages, the loading platform may be moved longitudinally of the supporting frame and will allow the forward end of the loading platform to be advanced and retracted in relation to the embankment from which the soil is being removed. 70

The loading platform 31 is constructed 75 with side frame members 46 and 47 which form supports for conveyer rollers 48 and 49 disposed at opposite ends of the frame and in parallel relation to each other, so that a conveyer belt 50 may be adapted to 80 be rotated in the direction of the arrow —a— as shown on Fig. 2 of the drawing by means of a motor 51 which is secured beneath the loading platform and is provided with a belt 52 adapted to rotate a pulley 53 85 secured to the shaft of the roller 48. It will be understood that other motive power could be used to drive the belt 50 without departing from the spirit of the present invention. The belt roller 49 is shielded 90 beneath a plate 54 which is molded over the forward tapered ends of the frame members 46 and 47.

Mounted through the frame members of the loading platform at a convenient point 95 adjacent their forward ends is a pivot shaft 55 upon which is rotatably mounted a pair of radial arms 56 and 59 within which a cutter shaft 60 is mounted. This shaft extends parallel to the belt roller shafts and has 100 fixed upon it a cutter drum 61 formed with longitudinally extending ridge portions against which cutter knives 62 and 63 are bolted. The knives designated by the numeral 62 act as scrapers as they extend the 105 full length of the rollers. The knives 63 are of slight width and act as teeth to break up and loosen the soil to be excavated. Either of these sets of knives may be removed as desired and readily interchanged 110 to meet the requirements produced by varying soil conditions.

The drum 61 is adapted to be operated by the motor 51 by means of a chain 64 which extends along the outside of frame 115 channel 47 and passes around a sprocket 65 secured upon a shaft 66 which extends across the loading platform between the upper and lower lengths of belting to the opposite side of the platform where it is 120 fitted with a gear 67. This gear is in mesh with a gear 68 which reverses the directing of rotation and causes the cutter drum to rotate in the direction of the arrow —b— in Fig. 1. Power is transmitted to the drum 125 from gear 68 by means of the chain 69 driven thereby and adapted to transmit movement of rotation to the pivot shaft 55. This shaft is fitted with a pair of sprockets 70 and 71 adapted to drive side chains 72 130

and 73 which lead to sprockets 74 and 75 secured to shaft 60 upon which the cutter drum 61 is mounted. In this manner the drum 61 may be rotated to act to draw the soil downward upon the end of the conveyer belt and further permit the drum to have radial movement in relation to pivot shaft 61 without interruption of the delivery of power thereto.

- 10 In operation, the machine is set up as shown in Fig. 1 of the drawings, and when the motor is supplied with electrical energy, operation will immediately take place. The forward end of the loading platform is positioned in relation to the embankment to be excavated so that the cutter drum will squarely encounter it. Afterward, a workman may grasp handle 77 secured to the side of the loading platform frame members 15 and swing the entire platform toward and away from the embankment as indicated by the arrow —c— of Fig. 1. As the platform and the cutter drum move forward, the carriages 23 and 30 advance along the tracks and beam, until the knives of the cutter drum encounter the soil. When the knives dig into the soil, they will loosen it and pull it downwardly onto the forward end of the loading platform, from whence 20 it will be conveyed and distributed along the conveyer belt. When the belt has been covered with the soil, it will be dumped from the upper end of the belt into wagons or trucks or may be elevated upon the loading platform by raising the platform in relation to its carriages. When it is desired to change the level at which the machine is cutting, the chain 38 may be lengthened and shortened as well as the chains 42 and 25 30 35 40 45 50 55 60
43. In this manner one man may easily control one machine. In case it is desired to raise and lower the forward end of the loading platform upon which is mounted the cutter drum, the lever 42 is manipulated to directly lengthen and shorten chain 38 as will be understood by examination of Fig. 1 of the drawings.

It will be further noted that by the peculiar arrangement of the cutter drum in relation to the loading platform an excessive quantity of soil may be fed beneath drum without choking the machine, as the drum will automatically rise above the mass of earth and operate without obstruction. 50 55 60 65 70 75 80 85 90 95 100 105 110 115 120 125 130

This feature of construction is also embodied within the modified form of the invention as disclosed in Fig. 7 of the drawings in which a conveyer belt 78 is employed in place of the cutter drum and provided with a series of tooth members 79 adapted to loosen the soil and drag it upon the loading platform.

As means for preventing back lash in the mechanism, a dragging brace 80 is provided 65 to wedge the conveyer and its cutter in its

forward operative position and prevent backward movement. Stop members 81 are also provided to limit the downward movement of the cutter drum and prevent damage to the machine.

70

In case it is desired to move the front end of the loading platform and its cutter drum, the beam 26 may be swung radially with its mast 24 as will be readily understood. The radial movement of the loading platform will be limited by the distance between uprights 13 and 15 of the supporting frame.

75

It will thus be seen that the excavating and loading machine as disclosed in the accompanying drawings and described in the specification provides simple and effective means for loosening, excavating and loading soil without requiring the attendance of a great number of workmen or the use of heavy power generating and transmitting machinery. It is also evident that the loading platform could be used without the necessity of using the cutter drum if desired, and furthermore, that the machine could be so designed as to be manually operated.

80

Special attention is called to the following important features. The cutter drum 61 provided with the cutting knives 63 and the scrapers 62 of the same height and adapted to cut to the same depth and extending longitudinally from end to end of the drum to tear up the hard material and scrape the fine material upon the loading belt of the draper 31, will dig just to the bottom of the draper nose, thereby allowing the draper or loading platform to slide in the space dug out by the cutter and making the feed automatic. If the machine were put into motion and not stopped, it would feed itself into an embankment, as far as the carriages and tracks would allow, by the action of the cutter drum pulling upon the draper and drawing the draper forwardly as fast as there is a clearance for it, and scraping a level and smooth surface with the nose of the draper to the bottom of the cut material. The drum would climb the embankment until the nose of the draper encountered resistance enough to stop, and then the cutter drum would dig up and down the face of the embankment and dig down to the level of the bottom of the draper and pull the draper forwardly as fast as the embankment is cut down. Of course, the supporting frame must be moved as often as the machine reaches the forward limit of travel upon the tracks. No matter how much of an embankment is in front of the machine, within reasonable limits, the cutting drum will travel up and down the face of the embankment and cut it away and as soon as the resistance at the nose of the draper is cut away by the cutting drum, the draper will advance by the pull of the cut-

110

115

120

125

130

ting drum upon the material. The stop 81 allows the cutting drum to go downwardly only to the level of the draper nose. As the embankment is cut away and the draper advances, the dragging braces 80 serve as pawls and the solid earth serves as the ratchet stops, thus holding the draper's nose to the embankment and preventing backward movement.

10 During this operation the cutting drum is rotating to cut downwardly, that is the side of the drum contacting with the bank is moving downwardly so that if the bank furnishes sufficient resistance it will elevate the 15 drum and when the resistance is cut away the drum will fall by gravity.

While I have shown the preferred construction of my excavating and loading machine as now known to me, it will be understood 20 that various changes in the combination, construction and arrangement of parts may be made by those skilled in the art without departing from the spirit of my invention.

25 I claim:

1. In an excavator and loader, a suitable support having a rigid elevated track and a swinging elevated track, carriages mounted upon the tracks, a platform suspended from 30 the carriages so that the forward end of the platform may swing laterally by the movement of the swinging track, a frame connected to the platform and projecting beyond the front of the platform and adapted 35 to swing up and down, a cutting drum mounted in the forward end of the frame and adapted to swing downwardly to a level with the bottom of the platform, and means

for operating the cutting drum to cut downwardly upon the face of an embankment. 40

2. In an excavating machine, a support, elevated tracks upon the support, carriages mounted upon the tracks, a platform suspended from the carriages, a cutting drum pivotally connected to the platform and extending forwardly, dragging braces carried by the platform, and means for operating the cutting drum to cut downwardly upon the face of an embankment; so that the cutting drum will climb an embankment, then 50 cut its way down, to remove the resistance in front of the platform, and then feed the platform forwardly.

3. In an excavating machine, a support, elevated tracks upon the support, a carriage 55 mounted upon said tracks, a platform, a flexible supporting connection between the carriage and one end of the platform, a horizontal track beam swinging above the elevated track, a carriage mounted upon said 60 track beam, means whereby the opposite end of the platform may be flexibly supported from the carriage upon said track beam, means for raising and lowering the end of the platform supported by the track beam, a 65 cutting drum pivotally connected to the platform and adapted to extend forwardly therefrom, means for adjustably holding the cutting drum in relation to the end of the platform, and means for operating the cutting drum to cut downwardly upon the face of an embankment and deliver the loosened material to the end of the platform. 70

In testimony whereof I have signed my name to this specification.

WILLIAM M. GROSS.
